LAST

Filed April 22, 1925

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed April 22, 1925. Serial No. 24,991.

My invention relates to lasts and in particular to a snap back last.

It is the object of my invention to provide a snap back last.

5 It is a further object of my invention to provide a snap back last in which the parts will be definitely and accurately located, the snap back spring definitely positioned and maintained in position and in which the 10 parts or links retaining the last parts together may be easily assembled in the minimum space.

15 It is a further object of my invention to provide a double link construction associated with a hinge pin which definitely ties the last parts together so that they will rock about the hinge pin as a center.

Referring to the drawings:

20 Figure 1 is a side elevation of a last partially in section to show the arrangement of the snap back spring and links; and

Figure 2 is a plan view of the link system with the hinge pin and anchoring pins broken away and with the spring in section.

25 Referring to the drawings in detail, 1 is the toe part of the last and 2 is the heel part.

The toe part is provided with a cut away slot 3 and the heel part with a cut away slot 4. The toe part has a semi-circular transverse cut away portion 5 in which a partially cylindrical shoulder transversely disposed and projecting from the heel part 2 fits. This shoulder is designated 6. The 35 lower adjacent portions of the heel and toe part are provided with shoulders 7 and 8 which engage with one another when the last is in expanded position. Such shoulders limit the expanding movement of the 40 last parts. The upper adjacent faces of the last parts are angularly disposed as at 9 and 10 forming roughly a V-shaped cut away portion between them when the last is in expanded position. This space 45 permits of the last halves approaching each other in collapsed position until the faces 9 and 10 engage.

The transverse hinge pin 11 is carried by the projecting circular shoulder 6 and is 50 located substantially in the center thereof. On this pin there is mounted a pair of heel

links which have closely adjacent portions 12. These links are bent at 13 outwardly from one another until they are suitably spaced so that there is an appreciable space 55 between their rearwardly spaced portions 14 which are provided with eyes at the rear ends thereof for mounting on the anchor pin 15 in the heel part.

The forward ends of these heel links 60 which ends are designated 12 are embraced on either side thereof by the spaced toe links 16 which are pivotally mounted on the hinge pin 11 at one end and mounted on the transverse toe anchor pin 17 at the 65 other end.

Between these spaced links 16 is located the arched spring 18, one end of which is provided with a hook 19 mounted on the anchor pin 17 and located between the toe 70 links 16.

The other end of this arched spring 18 is provided with a similar hook 20 mounted on the heel anchor pin 15 between the portions 14 of the heel links. 75

Thus the spring is maintained in its suitable position by these links which serve to connect the two parts together and hold them in a predetermined position.

It will be noted that the center of the pin 11 never goes below a line drawn between the centers of the pins 15 and 17 so that the spring 18 which is arched upwardly to clear the pin 11 will always tend to snap back the parts into expanded position. 85

It will be understood that I desire to comprehend within my invention such changes and modifications as may be necessary to adapt it to varying conditions of use.

Having thus fully described my invention, what I claim as new and desire to secure by Letters Patent, is:—

1. In a snap back last, a toe part and a heel part adapted to rock upon one another about a given center, a pin passing through 85 said center, links carried on said pin, pins in the last parts supporting the free ends of said links so arranged that a line drawn between the centers of said last mentioned pins will never pass over the center of the 100 first mentioned pin, and a spring mounted on said last mentioned pins arched over

said first mentioned pin to yieldingly resist the collapsing movement of the last parts about the center of the first mentioned pin.

2. In a snap back last, last parts adapted to rock one on the other, two pairs of links connecting said parts, each pair of links extending into respective parts of said last, a yielding connecting member arranged so

that its point of attachment through the last parts will not pass by the center of movement of the last parts, whereby a line drawn between the centers of attachment will always be below said center of movement.

In testimony whereof I affix my signature,
GEORGE CLAUSING.
